UNITED STATES PATENT OFFICE.

MICHAEL E. SULLIVAN, OF NEW BEDFORD, MASSACHUSETTS, ASSIGNOR OF NINE-SIXTEENTHS TO MICHAEL BUCKLEY AND W. WALDO ROBINSON, OF PAWTUCKET, RHODE ISLAND.

RING-SPINNING MACHINE.

SPECIFICATION forming part of Letters Patent No. 599,539, dated February 22, 1898.

Application filed October 4, 1897. Serial No. 654,017. (No model.)

To all whom it may concern:

Be it known that I, MICHAEL E. SULLIVAN, of New Bedford, in the county of Bristol and State of Massachusetts, have invented a new and useful Improvement in Ring-Spinning Machines; and I hereby declare that the following is a full, clear, and exact description of the same, reference being had to the accompanying drawings, forming part of this specification.

The invention has reference to the class of spinning-machines in which the bobbin, tube, or spindle on which the yarn is wound is driven and the drawn-out roving is twisted and laid on the bobbin, tube, or spindle by a traveler sliding on a ring.

Ring-spinning machines are driven at such high speed that the yarn between the traveler and the guide-eye above the axis of the spindle is, by the centrifugal force, thrown outward as it revolves around the spindle and interferes with the yarn of the adjacent spindles. Various forms of what are commonly known as "separators" have been used to prevent the interference of the yarn of one spindle with the yarn of adjacent spindles. These have usually been placed between adjacent spindles. The high speed of the revolving driving-cylinders, the bands connecting the spindles with the driving-cylinders, the spindles with the revolving yarn, and other moving or revolving parts of the mechanism of a ring-spinning machine keep the air below the inclosed top and between the rows of spindles on the two sides of the machine in constant agitation and produce strong air-currents, which, rushing inward near the floor and prevented from passing upward by the table or inclosed top of the machine, flow outward between the spindles and carry lint, floating fiber, and impurities to be caught by the rapidly-revolving yarn, the expansion or ballooning of which facilitates the collection of these floats on the yarn.

One object of my invention is to protect the yarn on its passage to the spindle against the air-currents and the floats carried by them.

Another object of my invention is to prevent excessive ballooning and the interference of the threads of adjacent spindles.

Figure 1 is a front view of the two end parts of a ring-spinning machine provided with my improvement, the central portion being cut out to reduce the length of the drawing. Fig. 2 is a transverse section of one side of the same. Fig. 3 is an enlarged sectional view of the curtain-rod.

In the drawings similar numerals of reference indicate corresponding parts in all the figures.

4 4 indicate the end frames of the machine; 5, the bolster-rail; 6, the reciprocating ring-rail; 7, the lifter-rods for operating the ring-rail; 8 8, the rings; 9, the bobbins, supported on the spindles 10 10; 11, the front beam; 12, 60 the top or board closing the space between the two front beams on opposite sides of the machine; 13, the finger-board, provided with the usual pig-tail wire or guide-eye 14, through which the yarn passes to the usual traveler 70 on the ring 8 and from this to the bobbin 9.

To the above-described usual parts of a ring-spinning machine I have added the curtain 15, secured by means of hooks, pins, or in any other suitable manner, detachably or 75 permanently, to the ring-rail 6 at the lower edge and to the curtain-roll 16, journaled in brackets 17, secured to the front beam 11 at the upper edge. The curtain-roll 16 may be one continuous roll extending the length of 80 the machine, or it may consist of a number of rolls. The curtain roll or rolls may be the usual well-known self-winding curtain-rolls in which a coiled spring acts to wind the curtain on the roll, or it may be provided at one 85 end with the cord 18, wound around a part of the curtain-roll 16 and provided at the suspended end with the weight 19.

To enable others skilled in the art to use my invention, I will now describe its operation more fully.

The curtain 15 may be made of any suitable flexible material. Ordinary cotton cloth answers all practical purposes. An open fabric which, while it allows air to pass through, prevents the float and lint to pass through may be used. One edge of the curtain, or a succession of curtains, being secured to the ring-rail and the other edge to the self-winding roller 16, the curtain adapts itself to the 100

reciprocation of the ring-rail and always keeps the space between the roller 16 and the ring-rail 6 closed, so that the air-currents and lint or float cannot reach the yarn as it passes to 5 the bobbin or spindle, thereby keeping the yarn clean and free from floats. The curtain 15 forms a flexible yielding surface along the rear of the row of spindles and sufficiently close to the same to prevent the excessive ballooning of the yarn and the interference 10 of the yarn of adjacent spindles.

In practice I find that it requires one or more turns of a spindle, even at the highest speed, to exert sufficient centrifugal force on 15 the yarn to cause it to bow outward or balloon perceptibly and that the yarn by coming in contact for a considerable length at each revolution with the surface of the curtain 15 does not acquire sufficient centrifugal force to bow outward or balloon so as to 20 come in contact with the yarn of the adjacent spindle. I further find that the spindles may be placed closer together than is now customary without the yarns of the adjacent spindles interfering with each other even at a 25 higher speed than is now generally used. Consequently the number of spindles in a machine may be increased as well as the speed and a corresponding increase in the production 30 secured.

It is also obvious that the curtain 15, whether fixed or rolling, prevents floats from being carried in between the spindles from the front and limits the ballooning of the yarn.

35 Having thus described my invention, I

claim as new and desire to secure by Letters Patent—

1. In a ring-spinning machine, the combination with the spindles, the reciprocating ring-rail, of a curtain secured to the ring-rail, 40 and a self-winding curtain-roll supporting the upper part of the curtain and located in a plane above the ring-rail, whereby the yarn is protected against floats and excessive ballooning, as described. 45

2. In a ring-spinning machine, the combination with the front beam and the ring-rail of the machine, of the roller 16 supported in suitable bearings above the highest reciprocation of the ring-rail, a curtain secured to the roller 50 and to the ring-rail, and means, substantially as described, for automatically rolling up and letting out the curtain, whereby the space between the ring-rail and the front beam is closed by the curtain. 55

3. In a ring-spinning machine, the combination with the spindles, the reciprocating ring-rail and the front beam of the roller 16, the cord 18, the weight 19 and the curtain 15 secured to the roller and to the ring-rail, 60 whereby the curtain is automatically adjusted to close the space between the ring-rail and the front beam, as described.

In witness whereof I have hereunto set my hand.

MICHAEL E. SULLIVAN.
